UNITED STATES PATENT OFFICE.

GRANT D. BRADSHAW, OF WESTMONT BOROUGH, PENNSYLVANIA.

STOVE-BURNER.

1,157,841.

Specification of Letters Patent. Patented Oct. 26, 1915.

Application filed July 15, 1915. Serial No. 39,955.

To all whom it may concern:

Be it known that I, GRANT D. BRADSHAW, a citizen of the United States, residing in the borough of Westmont, in the county of Cambria and State of Pennsylvania, whose post-office address is Johnstown, Pennsylvania, have invented certain new and useful Improvements in Stove-Burners; and I do hereby declare the following to be a full, clear, and exact description of the invention, such as will enable others skilled in the art to which it appertains to make and use the same.

My invention consists generally of a burner adapted to permit the combustion of combustible gas or gases and air and is particularly adapted for use in what is known as hot-blast stoves, although it may be used on heating furnaces, boiler furnaces or for any purpose where heat is required. My stove burner is also especially adapted for thoroughly mixing and aiding the combustion of blast furnace gases, which ordinarily are of comparatively low calorific value, requiring, by reason of this fact, a very thorough and carefully regulated mixture of air and these gases. It is also well adapted to assist the combustion of what is known as producer-gases, which, similar to the blast furnace gases, contain a very large proportion of nitrogen and incombustible elements.

My burner consists of a pipe or tube of substantially uniform section, preferably provided with an elbow or turn of considerable radius, in order to insure a uniform flow of gases therethrough, in which tube I mount a construction whereby the area thereof is restricted and the gas velocity is consequently made greater in its vicinity.

From the point of the greatest size of this obstruction I taper it down to a comparatively sharp point near the exit end of the tube; thus giving the effect at the outer end of an expanding or increasing section and reducing the friction and eddying losses to a minimum. At the point of the greatest contraction of the tube, due to the obstruction placed therein and near the point of the highest velocity of the gases I provide within the obstruction, which is hollow, a number of openings which are connected to the external or other sources of air supply by a tube or pipe of smaller size than the main gas pipe. By reason of this construction, the total head at the burner outlet is composed of two items; namely, the static

head and the velocity head, and as the stove in question contains gases at or about atmospheric pressure, the total head is the velocity head alone. At the point of highest velocity in the burner the total head, due to the absence of losses by reason of the expanded cone construction, is equal to the total head at the outlet end of the burner. As, however, the velocity head at the point of greatest velocity is greater than the velocity head at the outlet end of the burner, the static head at the point of greatest contraction must be negative, or a minimum quantity and consequently if opportunity is given for the external air to enter at this point it will do so, and it will be drawn into the burner at a velocity proportional to the square root of this negative head. As the square root of this negative head is also proportional to the gas velocity, it naturally follows that the gas and air velocity will also be proportional to each other, whereby the result of my construction is accomplished, and consequently the mixture of air and gas automatically regulates itself, so that the combustion is perfect notwithstanding a wide variation or range in the velocity or pressure of the gases which are supplied to the burner. The openings in the outer gas burner tube may be considered as auxiliary and are provided for the purpose of giving a greater area for the inlet of air with the combustible gases in the burner, as in some instances these additional exterior openings are needed for the reason that on account of the comparatively small size of my interior air inlet pipe the burner must have enough area of air openings at or near the contracted portion, so that this air shall be supplied in accordance with my invention.

Having thus given a general description of my apparatus and its mode of operation, I will now, in order to make the matter more clear, refer to the annexed sheet of drawings, which form part of these specifications and in which like characters denote like parts.

Figure 1 is a vertical cross sectional elevation through my burner and through the opening in the wall of a furnace or hot-blast stove, Fig. 2 is an end elevation of my burner looking toward the outlet or discharge end thereof and Fig. 3 illustrates the air damper which is used in connection with my air supply, but I wish it understood

that a butterfly or other style of damper may be used with equally good results.

Referring now to the characters of reference on the drawings, 1 indicates the wall of the furnace or hot-blast stove, 2 is the gas or fuel opening therein, 3 is the main gas pipe of my burner to which blast-furnace or producer or other gases may be introduced under such pressure as is available or desirable; 4 is the flange surrounding the exit end of my gas burner to close up the annular space between the burner and the opening in the furnace or stove wall, 5 are the auxiliary air openings in the external pipe 3, the size of which may be readily regulated by the flanged sleeve 6, which is adapted to loosely fit over the burner pipe and can be slid backward or forward to open or close the openings 5 more or less as desired. I provide a main air inlet pipe of smaller size than the gas burner pipe, which air pipe is indicated as 9 and passes through the opening 7 in the gas burner pipe and 8 is a flange surrounding the same and fitting against the outside portion of the burner to close the small space between pipes 9 and 3. Within the pipe 3 and near the exit end thereof I provide a cone-shaped construction 10, the end of which 11 is of small size or drawn to a point. The inner end of the air pipe 9 is formed of increasing diameter, or as of truncated cone section, as indicated at 12, and is also provided with the air openings 13 adapted to communicate with the interior of the gas burner 3 in one direction and with the external air from the main air pipe 9 in the other direction. At the outer end of the auxiliary air pipe I provide a grooved flange 14 adapted to fit thereon, and in the grooves thereof, I provide a sliding damper 15, whereby the amount of air entering into pipe 9 may be regulated or cut off entirely if desired. In order that my apparatus shall work to the best advantage with different kinds of gases, which, on account of their varying composition, require different amounts of air for combustion, I set the damper 15 on the main inlet for substantially the correct amount of air to be mixed with the particular gas employed. On account of the central location of the outlets 13 of the main air inlet pipe 9, these supply the major portion of the air for the combustion of the gas, and under certain conditions no air whatsoever is needed to be added through the auxiliary air openings 5, and under these conditions the flanged sleeve 6 is set to close these openings 5. Under other conditions, however, which are ascertainable by actual operation, I may admit some air through the auxiliary air openings

5 by setting the flanged sleeve 6 to expose more or less of the said openings 5 in order to insure the most perfect mixture and combustion of gas and air. In order to obtain a thorough and proper mixture of the gases I regulate the slide damper 15 and the sleeve damper 6 so that the combustible gases passing through the burner pipe 3 are thoroughly mixed with air just before they enter the combustion chamber 2.

Although I have shown and described my invention in considerable detail, I do not wish to be limited to the exact and specific details shown and described, but may use such substitutions, modifications or equivalents thereof, as are embraced within the scope of my invention or as pointed out in the claims.

Having thus described my invention, what I claim and desire to secure by Letters Patent is:

1. A gas burner comprising a burner tube, an inclined or flaring obstruction located near the exit end thereof, whereby the cross-sectional area is gradually reduced, said obstruction then tapering inwardly whereby the cross-section is gradually increased, air inlet openings near the reduced portion of said cross-section and means for regulating the size of said openings.

2. A gas burner comprising a burner tube, a plurality of openings near the exit end thereof, an air inlet tube projecting into said burner tube and increasing in diameter toward the exit end and then decreasing in size toward said exit end, whereby the area of said burner tube is first contracted and then expanded toward its exit opening; inlets in the air inlet tube, and means for controlling the size of the air inlets aforesaid.

3. A gas burner comprising a burner tube, provided with a series of openings near the exit end thereof, a slide ring damper adapted to control the size of said openings, an air inlet tube projecting into the gas burner tube aforesaid and provided on its outer end with air regulating means, said inlet tube increasing in diameter and then decreasing toward the exit end, and a plurality of air openings in the inlet tube connecting with the interior of said burner tube, whereby the mixture of gas and air is automatically controlled throughout a considerable range of pressure of entering gases.

In testimony whereof I hereunto affix my signature in the presence of two witnesses.

GRANT D. BRADSHAW.
